Primary Examiner — Jae Liang*Assistant Examiner* — Tia Ruth-Renee Polidori(74) Attorney, Agent, or Firm — Millburn IP PLLC(57) CLAIM

The ornamental design for a drinking cup, as shown and described.

DESCRIPTION

FIG. 1 is a top perspective view of a drinking cup, showing our new design;

FIG. 2 is a side elevational view of the drinking cup of FIG. 1; other side elevational views are the same;

FIG. 3 is a top plan view of the drinking cup of FIG. 1;

FIG. 4 is a bottom plan view of the drinking cup of FIG. 1; FIG. 5 is a bottom perspective view of the drinking cup of FIG. 1; and,

FIG. 6 is a cross-sectional view of the drinking cup along the 6-6 line shown in FIG. 3.

The broken lines depict cross-sectional view indicia, and form no part of the claimed design.

1 Claim, 5 Drawing Sheets(56)
